US0D1073679S

(12) **United States Design Patent** (10) **Patent No.:** **US D1,073,679 S**
(45) **Date of Patent:** **** May 6, 2025**

(54) **GAME CONTROLLER**

(71) Applicant: **Microsoft Corporation**, Redmond, WA (US)

(72) Inventors: **Monique Chatterjee**, Seattle, WA (US); **Corrie Greening**, Seattle, WA (US); **Matthew Harvey**, Boston, MA (US); **Forrest Major**, Scituate, MA (US); **Grant Dyer**, Providence, RI (US); **Austin Clark**, Lansing, MI (US)

(73) Assignee: **Microsoft Corporation**, Redmond, WA (US)

(**) Term: **15 Years**

(21) Appl. No.: **29/979,671**

(22) Filed: **Dec. 19, 2024**

(51) LOC (15) Cl. **21-01**

(52) U.S. Cl.

USPC **D21/333; D14/401**

(58) **Field of Classification Search**

(57) **CLAIM**

The ornamental design for a game controller as shown and described.

DESCRIPTION

FIG. 1 is a bottom perspective view of a game controller according to the present invention.

FIG. 2 is a top perspective view of the game controller of FIG. 1.

FIG. 3 is a front view of the game controller of FIG. 1.

FIG. 4 is a right view of the game controller of FIG. 1.

FIG. 5 is a left view of the game controller of FIG. 1.

FIG. 6 is a bottom view of the game controller of FIG. 1.

FIG. 7 is a top view of the game controller of FIG. 1; and, FIG. 8 is a rear view of the game controller of FIG. 1.

The broken lines in the figures show portions of the game controller and form no part of the claimed design.

1 Claim, 8 Drawing Sheets
